[57] CLAIM

The ornamental design for a nail-tip setter, as shown and described.

DESCRIPTION

FIG. 1 is a left side-elevational view of a nail-tip setter showing my new design thereof;

FIG. 2 is a top plan view thereof;

FIG. 3 is a bottom plan view thereof;

FIG. 4 is a right side-elevational view thereof;

FIG. 5 is a rear-elevational view thereof; and,

FIG. 6 is a front-elevational thereof.
